CLAIM

The ornamental Design for an exercise suit, as shown and described.

DESCRIPTION

FIG. 1 is a front perspective view of a first embodiment of my design, showing a man's exercise suit, having a vest and shorts according to the present invention;

FIG. 2 is a rear perspective view of a first embodiment of my design, showing a man's exercise suit, having a vest and shorts according to the present invention;

FIG. 3 is an inside view of a first embodiment of my design, showing a man's exercise suit, having a vest and shorts according to the present invention;

FIG. 4 is a front perspective view of a second embodiment of my design, showing a woman's exercise suit, having a vest and shorts according to the present invention;

FIG. 5 is a rear perspective view of a second embodiment of my design, showing a woman's exercise suit, having a vest and shorts according to the present invention; and,

FIG. 6 is an inside view of a second embodiment of my design, showing a woman's exercise suit, having a vest and shorts according to the present invention.
